UNITED STATES PATENT OFFICE

DANIEL S. PFAHL, OF CLEVELAND, OHIO

FILLING-PIPE CAP

Application filed June 25, 1926. Serial No. 118,404.

This invention relates to filling attachments for tanks and has particular reference to a compound closure which is adapted to be secured to the filling neck of the usual underground tank such as is used in connection with 5 gasoline filling stations.

The main object of the invention is to provide a closure attachment which can only be opened by the wholesale dealer or his representative, thus preventing the filling of the 10 tank with any other brand of gasoline and thus insuring the customer of receiving the particular brand advertised.

Also in certain parts of the country, it has 15 been customary for the manufacturer of tanks and dispensing equipment to furnish the retail dealer with equipment and to charge the retailer a certain percentage on the gasoline or other commodity dispensed through such equipment, the dealer agreeing to purchase 20 gasoline only from the manufacturer. With tanks heretofore known it has been possible for a dishonest dealer to purchase gasoline, oil or other commodity from a person other 25 than the one who furnished the equipment.

One of the objects of this invention is to provide a closure attachment for tanks which has a plurality of closures, the key to one of such 30 closures being retained by the wholesale dealer and the key to the other of said closures to be in the possession of the retail dealer.

Another object of the invention is to provide a closure attachment of the class described which is simple and rigid in construction and which is well adapted for quantity 35 production at comparatively low cost.

Another object of the invention is to provide a closure which, when attached to the filling neck of the usual underground gasoline tank, can be removed for filling or refilling only by an authorized representative 40 of the wholesale dealer.

Further and more limited objects of the invention will appear as the description proceeds and by reference to the accompanying 45 drawing in which Fig. 1 is a view partly in section and partly in side elevation showing my attachment secured to the filling neck of the usual underground tank and Fig. 2 is a 50 top plan view of the same.

Referring now to the drawing the numeral 1 designates the usual underground tank provided with a filling neck 2 threaded at its upper end as shown at 3. The numeral 4 designates an annular base member having a 55 threaded opening 5 therein adapted to be secured about the filling neck 2. Formed about the opening 5 is an annular shoulder 6 and the upper end of the filling neck is adapted to be peened over onto this shoulder for securing 60 the annular base member against removal from the filling neck 2. Pivottally secured to the annular base member 4 is a cover plate 7 having an opening 8 therein, the opening 8 being considerably smaller than the opening 5, the purpose of which will hereinafter appear. Pivottally secured to the plate 7 is a cap 9 which is adapted to close the opening 8 in the cover plate 7. The annular member 4 is also provided with an aperture 10 which 65 is adapted to align with a similar aperture 11 in the plate 7 when the parts are in the position shown in Fig. 1. The plate 7 is locked to the annular base member 4 by means of a lock 12. The plate 7 is also provided with a 70 pair of spaced apertured lugs 13 and 14 adapted to receive therethrough a second lock 15 for securing the cap 9 in closed position. The opening 8 in the plate 7 is considerably smaller than the opening 5 and is only of sufficient size 75 to allow an ullage rod or other suitable measuring instrument to be inserted therethrough for determining the amount of liquid contained within the tank 1. This opening 8 is so small that it will be very difficult if 80 not impossible to refill the tank 1 without removing the plate 7.

Operation

The tank 1 is adapted to be filled by the 90 wholesale dealer who has a key to the lock 12. When the lock 12 is removed the plate 7 may be moved to give access to the opening 5. The wholesale dealer fills the tank through this opening and closes and locks the plate 7. The 95 retail dealer who retains the key to lock 15 may open the closure 9 and insert an ullage rod to determine the quantity of liquid in the tank 1 and should the tank need replenishing he may notify the dealer who will again fill 100

the tank. When the tank 1 has been filled with a certain grade and quality of gasoline or other commodity and the plate 7 locked in place, the tank 1 cannot again be tampered with and the customer is insured of receiving a certain grade and quality of gasoline.

It will now be clear that I have provided a device which will accomplish the objects of the invention as hereinbefore stated.

10 Having thus described my invention, what I claim is:

1. A closure attachment of the class described comprising an annular member having an opening therein adapted to receive the upper end of the filling neck of a tank, a shoulder formed adjacent said opening whereby a part of said filling neck may be bent over to secure said annular member to said neck, a plate pivotally secured to said annular member, said plate having an opening therein smaller than the opening in said annular member, a cap pivotally secured to said plate and adapted to close the opening therein, means for locking said plate in closing position and means for locking said cap in position to close the opening in said plate.

2. A closure attachment for tanks comprising an annular member adapted to be secured about the filling neck of a tank, a plate pivotally secured to said annular member and having an opening therein of less diameter than the opening in the said annular member, a cap pivotally secured to said plate and adapted to close the opening therein, means for locking said plate to said annular member and means for holding said cap in position to close the opening in said plate.

3. A closure attachment of the class described comprising a member having an opening therein adapted to receive the upper end of the filling neck of a tank, a shoulder formed adjacent said opening whereby a part of said filling means may be bent over to secure said member against removal from said neck, a plate secured to said member, said plate having an opening therein considerably smaller than the opening in said annular member, a cap carried by said plate and adapted to close the opening therein, means for locking said plate in closing position and means for securing said cap in position to close the opening in said plate.

In testimony whereof, I hereunto affix my signature.

55

DANIEL S. PFAHL.
